O. W. BLANCHARD

COLLAPSIBLE BOWLING ALLEY

Filed Jan. 31, 1924

INVENTOR:

Owen W. Blanchard

BY A. M. Carlsen
ATTORNEY.

UNITED STATES PATENT OFFICE.

OWEN W. BLANCHARD, OF ST. PAUL, MINNESOTA.

COLLAPSIBLE BOWLING ALLEY.

Application filed January 31, 1924. Serial No. 689,616.

To all whom it may concern:

Be it known that I, OWEN W. BLANCHARD, a citizen of the United States, residing at St. Paul, in the county of Ramsey and State of Minnesota, have invented certain new and useful Improvements in Collapsible Bowling Alleys, of which the following is a specification.

This invention relates to game apparatus and the object is to provide a portable and foldable bowling alley of such construction that it may be easily knocked down and stored in a comparatively small space and readily set up again for use in one or 15 more rooms, thus affording a domestic alley for amusement and practice.

In the accompanying drawing:

Fig. 1 is a top or plan view of the improved bowling alley.

Fig. 2 is a side elevation of Fig. 1.

Fig. 3 is an enlarged section on the line 3-3 in Fig. 2.

Fig. 4 is an enlarged section on the line 4-4 in Fig. 1.

Referring to the drawing by reference numerals, 5 designates the alley proper which is an elongated plane made up of hard wood strips secured on cross cleats 6 and given a smooth top surface for the balls 30 to roll on as from the left in Figs. 1 and 2 toward the pit 7 shown at the right. Said pit is surrounded at three sides by a vertical guard 8 which is provided with stakes 9 detachably placed in sockets 10. Said 35 guard may have hinges 11 in its corners to make it foldable when it is to be removed from the alley.

Attached to each side or edge of the main alley 5, by hinges 12, is a gutter 13 with a 40 raised guard 14 at its outer edge while the gutter itself slopes gently downward toward the left end of track 5.

The entire track or alley and its gutters are divided transversely into several sections. In the present drawing three sections A, B, C the adjacent ends are at each 45 joint 17 formed with a tongue 15 fitting snugly in a groove 16 (see Fig. 4) so as to insure an even surface at the top of the 50 alley. Each joint 17 rests on a supporting block 18 placed upon the floor 19 and provided with inserted bolts 20 having each a wing nut 21. Slightly spaced away from each block 18 are angular brackets 22 secured under the ends of each alley section, 55 preferably to the cleats 6 thereof, and hav-

ing each a downwardly directed flange with a notch 23 arranged to receive the adjacent bolt 20 and be drawn toward each other or the intervening block 18 until the joints 17 60 are perfectly tight. Besides the blocks 18 there may be several loose blocks 18^a placed between cleats 6 and supporting the main alley 5 and its side gutters 13.

In the operation of the device, it is placed 65 on the blocks 18-18^a in a hall, a large room, or two adjoining rooms and the door opening between them and played in the usual manner by placing the regular bowling pins as at 24 near the pit 7 and knocking them down by rolling balls 25 in the direction of arrow 26 in Fig. 1. The balls 70 are picked up from the pit 7 and returned by way of the gutters 13, as indicated by the ball 25 in Fig. 3.

When the apparatus is to be stored or shipped, the blocks 18-18^a are removed, the sections A, B, C are separated and on each of them the gutter sections are turned on the hinges 12 until folded under the main 80 body section, as shown in dotted lines in Fig. 3. This admits of placing the blocks 18-18^a and the folded guard 8 between the folded gutter sections 13 whereby the whole device may be put away in the minimum of 85 space when not in use.

The alley may be made in various sizes for use in a dwelling or outdoors. The main thing is to provide a bowling alley that is easy to set up and take down and which 90 will occupy very little space when not in use.

What I claim is:

1. In a bowling alley comprising a portable bowling track divided transversely into abutting sections, removable blocks supporting the adjacent ends of the sections and means for securing the ends of the sections firmly together, each of said sections having longitudinal side portions serving as return gutters for the balls used in the game, said gutters being hinged to the main section and adapted to rest on the same supporting blocks as the main section and to be folded underneath the latter when the supporting 100 blocks are removed.

2. The structure specified in claim 1, and other removable blocks supporting other parts of the track and comparatively thin cleats fixed at the bottom side of the track 110 one at each side of each supporting block.

3. The structure specified in claim 1 in

which the securing means comprise angular brackets secured underneath the sections and having each a flange with a downwardly open notch, a bolt carried by the supporting block in position to enter said notches, said bolt having a head and a nut by which to engage the flanges and draw the sections tightly together.

4. The structure specified in claim 1 in
10 which the sections have thin transverse cleats fixed to the under side near the ends thereof, and angular brackets secured to said cleats, and bolts arranged to draw said

brackets toward each other and thereby force the ends of the sections tightly together.

5. A bowling alley having a track with a pit at one end thereof and a detachable guard arranged about both sides and the outer end of the pit, in which said guard is 20 made of sections hinged together so as to be foldable into a small space.

In testimony whereof I affix my signature.

OWEN W. BLANCHARD.
